UNITED STATES PATENT OFFICE.

JOHN HART, OF BRUNNERTON, GREYMOUTH, NEW ZEALAND.

HAT-FASTENER.

1,268,569.

Specification of Letters Patent.

Patented June 4, 1918.

Application filed June 15, 1915. Serial No. 34,309.

To all whom it may concern:

Be it known that I, JOHN HART, a subject of the King of Great Britain, residing at Brunnerton, Greymouth, New Zealand, have 5 invented certain new and useful Improvements in Hat-Fasteners, of which the following is a specification.

My invention relates to hat fasteners, and more particularly to a hat fastener permanently carried by the hat or similar head gear and adapted to engage the hair. Of course, it is to be understood that this hat fastener is more particularly adapted for use in connection with ladies' hats. 10 The primary object of my invention is to provide a hat fastener which is simple in construction, cheap to manufacture, effective in operation, and one which is strong and durable.

A further object of my invention is to provide a hat fastener which may be quickly and easily mounted on a hat, and may be readily operated from the exterior thereof.

A still further object of my invention is 25 to provide a suitable supporting frame for the fastening members and a handle member protruding exteriorly of the hat to operate the fastener.

With the above and other objects in view 30 my invention resides preferably in the construction, combination, and arrangement of parts as hereinafter set forth in the specification and illustrated in the accompanying drawings, in which—

Figure 1 is a longitudinal sectional view 35 through a hat or similar head gear showing my invention applied.

Fig. 2 is a fragmentary sectional view taken on the line 2—2 of Fig. 1.

Fig. 3 is a perspective view of the fastener.

Fig. 4 is a side elevation of the fastener showing one plate thereof removed.

Similar reference characters indicate similar parts throughout the various views of the drawings.

Referring more particularly to the drawings in which the preferred embodiment of my invention is illustrated, the numeral 1 50 designates the crown of a hat and the numeral 2 the brim thereof. The crown 1 is provided with the usual top 3.

My improved fastener comprises a pair of parallel arranged spaced-apart plates 4 and 5 supported in the above-mentioned relation by means of bolts or the like 6 hav-

ing engagement with spacing studs 7 carried by one or the other of the plates 4 and 5. The opposite extremities of the plate 4 extends slightly beyond the extremities of the plate 5 as indicated at 8 and are provided with suitable openings 9 for securement to the crown 1 by stitching or the like. As indicated in Fig. 1 the plate 4 is secured by means of stitches 10. As indicated in Fig. 3 the configuration of the plates 4 and 5 should conform to the configuration of the crown 1 of the hat but this is not necessary. The curvature of the plates 4 and 5 has been slightly exaggerated 70 in Fig. 3 for the purpose of conveying the arrangement more easily.

The fastening means comprises a pair of curved prongs 11 and 12 carried by pinions 13 and 14, respectively, said pinions being 75 mounted on shafts 15 and 16, respectively, and preferably disposed between the plates 4 and 5 as illustrated to advantage in Fig. 3. The pinions 13 and 14 are preferably intermeshing and adapted for opposite rotation. 80 The outer extremities 17 and 18 of the prongs 11 and 12 are adapted, when in clasped position to lie in overlapping relation. The relative positions of the fastening prongs 11 and 12 should be such that when 85 one of the same is in open position, the other prong will also be in open position.

The shaft 15 is preferably extended beyond the outer surface of the crown 1 of the hat as indicated at 19, and the outer extremity thereof is reduced as indicated at 20 to receive a handle member 21 which may be detachably mounted thereon so as to facilitate securement of the device to a hat. It will be noted that the reduced portion 20 of 95 the shaft 15 is sharpened to provide a point 22 for a purpose which will be hereinafter set forth.

I desire to lay particular stress upon the peculiar manner in which the free extremities 17 and 18 of the prongs 11 and 12 will overlap when the same are in fastened position. It will be noted that rotation of the shaft 15 in the direction indicated by the arrow in Fig. 3 will cause the pinion 13 100 carrying the fastening prong 11 to rotate therewith. Motion will be imparted to the pinion 14 carrying its respective prong 12 in the opposite direction in which the prong 11 moves. It will thus be seen that the two 105 fastening prongs 11 and 12 will be caused to engage the hair of the user's head and

lie in relatively overlapping engagement with the hair, so that accidental removal of the hat or similar head gear from the head is prohibited.

5 A more secure engagement with the hair is provided by virtue of the fact that the prongs 11 and 12 are receivable between the spaced-apart plates 4 and 5 so that bending or twisting of the prongs when fastened is
10 prohibited.

While I have shown and described my invention as possessing a peculiar form and construction, it is desired that it be understood that I may make such changes in
15 the details thereof that do not depart from the spirit and scope of the invention as claimed.

Having thus described my invention what I claim and desire to secure by Letters Patent is;

In a device of the class described, the

combination of a plurality of spaced plates, curved prongs pivotally mounted upon said plates and when in an open position extending from opposite sides of said plates, said prongs being adapted to be swung to a closed position so as to cause the ends thereof to be received between said plates, thus shielding the ends of the prongs to prevent the same from injuring the head of the user, and also reinforcing the prongs at their ends, as well as the pivot portions, thus preventing a side springing of the prongs which might allow the hair gripped thereby to be accidentally disengaged.

30 In testimony whereof I affix my signature in presence of two witnesses.

JOHN HART.
